United States Patent Office

Des. 175,302
Patented Aug. 9, 1955

175,302

HOOK

James G. Gale, Kansas City, Mo., assignor to Newman Manufacturing and Sales Company, Kansas City, Mo., a corporation of Missouri

Application May 18, 1955, Serial No. 36,080

Term of patent 14 years

(Cl. D54—11)

Fig. 1.

Fig. 2. Fig. 3.

Fig. 4.

INVENTOR.

Fig. 1 is a side elevational view of a hook showing my new design.

Fig. 2 is an end elevation of the hook taken from the left side of Fig. 1.

Fig. 3 is an end elevational view of the hook from the end opposite Fig. 2.

Fig. 4 is a plan view of the hook.

I claim:

The ornamental design for a hook, as shown.
